UNITED STATES PATENT OFFICE.

EMILE MARIE PAUL AMANN, OF PARIS, FRANCE.

PIVOTING FRAME FOR LATHES OF THE REPRODUCING TYPE.

Application filed September 8, 1924. Serial No. 736,622.

To all whom it may concern:

Be it known that I, EMILE MARIE PAUL AMANN, a citizen of France, and a resident of Paris, France, have invented new and useful Improvements in Pivoting Frames for Lathes of the Reproducing Type, which is fully set forth in the following specification.

The present invention relates to a pivoting frame for lathes serving for the reproduction of various objects according to a given model, and chiefly for lathes adapted for the reproduction of shoe lasts.

The said frame chiefly provides for the turning of two pieces of work mounted in a symmetrical position, whereof one is made to conform to a given model or is derived therefrom according to stated characteristics.

The principles of the present device relate to the following features:

(a) the arrangement is very rigid and cannot be put out of shape.

(b) the axial lines can be adjusted with facility.

(c) a strong construction is provided for the centres of oscillation at the middle part of said frame.

(d) ample space for turning purposes is provided between the points and relative to the diameter.

(e) elimination of all play of the gear teeth between the shaft of the model and the shaft of the pieces of work.

(f) suitable displacement of the lathe stocks whereby the model can be readily observed and controlled.

(g) the inertia and the resiliency are reduced to a minimum.

The following description relative to the appended drawings which are given by way of example shows an embodiment of the said invention.

Figs. 1 and 1^a constitute a front elevation of a machine embodying the present invention, and

Figs. 2 and 2^a constitute a side elevation of the apparatus shown in Figs. 1 and 1^a.

Upon the tubular steel shaft 1 of large cross section are mounted two substantial ball-bearings 2, 2^a which are disposed without the bored-out portion of the bearings 3, 3^a pertaining to the main structure of the lathe 4, which is shown in the dot and dash lines, Figs. 2 and 2^a. Between the sets of bearings 3, 2 and 3^a, 2^a and also at the sides

of the same, are mounted upon the said tube 55 the aluminium hubs 5, 7 and 7^a which are bored and split, and are maintained by cross-bolts. The central hub 5 consists of a long split cylinder having integral therewith a hollow trapezoidal prismatic portion 5^a, Fig. 1, which is traversed by a shaft 6, tangent to the tube 1. It will be observed in Fig. 2 that the hubs 7 and 7^a and the portion of the prism 5^a situated above the hub 5 are not in line with the part of the prism 5^a situated below the said hub.

The end hubs 7 and 7^a, as well as the prism 5^a each have machined surfaces a, a^a, b, b^a, c, c^a, Fig. 1. Upon the three surfaces a, a^a are respectively disposed the movable stocks 8, 8^a, 8^b. Upon the face b, b^a is mounted the stationary stock 9 which comprises two claws 10, 10^a by which the pieces of work 13, 13^a can be actuated. Upon the face c, c^a is mounted the stationary stock 11 within which is disposed the shaft 12^a carrying the model; the model 12 is held between the point 21 of the stock 8^b and the claw of the stock 11. The rotation of the shaft of the model 12^a is imparted to the pieces of work 13 and 13^a by the bevel gears 14 and 15 which are disposed within the stock 11, and by the bevel gears 16 and 17 disposed within the stock 9, the gear 14 being keyed to the shaft carrying the claw 19, and the gear 17 being keyed to a shaft carrying the claws 10 and 10^a. Since bevel gears are employed for the drive, the wear of said gears can be taken up by a displacement of the same upon their axes. In this manner sharp edges can be obtained upon the pieces of work, the same depending upon the reactions of reversal of pressure upon either side of the gear teeth, so that the present device will thus afford accuracy as well as a strong construction due to the use of large gear teeth.

The claws 10 and 10^a and the claw 19 must be situated at very exact distances from the central axis, and in consideration of the dimensions of the pivoting frame, the object of the invention, it may happen that the boring machine which is employed is not sufficiently accurate, but the disposition adopted for the mounting of the stocks 9 and 11 which may be set by means of thin strips and pins will provide for an exact as well as steady position of the claws 10, 10^a and 19.

The points 20 and 20^a can be adjusted in

like manner, but their angular position relative to the said claws can also be changed by turning, upon the shaft 1, the hubs 7 and 7¹ which are then clamped in their new position.

5 The arrangement of the stocks 8, 9 and 8¹ in the W form permits work of large diameter to be turned in the lathe, due to the large space between the branches of the W.

The use of the bolts situated upon the 10 faces a, a¹, which have a uniform spacing, will also provide for each of the movable stocks 8, 8¹, 8² a certain number of longitudinal positions depending upon the number of holes, by the progressive displacement 15 of the stocks upon their supports (three in the present case).

In order to bring each of the points 20, 20¹ and 21 into the desired position, it will suffice to act upon the respective hand 20 wheels 27², 27, 27¹ which are secured to the screwthreaded portions 23, 22, 21¹, thereby displacing the nuts 25, 24, 24¹ and hence the sockets 26², 26, 26¹ secured to the points 20, 20¹, 21, respectively.

25 Fig. 2 shows the said pivoting frame in the operative position, wherein its arm 32, which is secured to the prismatic element 5¹ and braced at the upper part by the hand rail 33, is brought back by the elastic member 31 in such manner that the model 12 enters into contact with the tracing element 30. This latter is supported in the known manner by the slide 50 which is moved forward in the same manner as the upper slide 36, due to the rotation of the drum 35. The slide 36 is provided with the cutters 37 acting upon the pieces of work 13 and 13¹.

30 It should be observed that in the inoperative position of the frame shown by the dotted lines at 34, Fig. 2, a great advantage is had by the relative displacement of the axes of the parts of the said frame situated above and below the central tube 1, for if the said parts had no such displacement, the 35 lower part 34 would enter into contact with the controlling drums 35; further, the said displacement provides for a suitable position of the shaft 6 connecting the model shaft with the working shaft, in which it 40 will not come into contact with the central tube.

The eye of the workman occupied with the said machine, Fig. 2, is enabled to observe the model as well as the reproducing 45 element 30 which he controls, and also the piece of work, and he also observes the said cutters when in operation.

50 The movement of rotation is imparted to the shaft of the model through the medium of the pulley 39 which is keyed to the end of the shaft 38 disposed within the tube 1 and whereof the end has mounted thereon the supporting pulley 40, connected by belt with the pulley 41 which is keyed to the 55 shaft of the model 12¹.

Obviously, the said arrangements are susceptible of modifications in detail without departing from the principle of the invention.

What I claim is:

1. A pivoting frame for reproducing lathes comprising a stationary shaft, a sleeve clamped to the said shaft and forming a hub, an arm integral therewith and extending in a direction perpendicular to the axis of the shaft, a stock adjustably mounted upon said arm, a claw revoluble in said stock, a second stock situated opposite the first-mentioned stock and cooperating therewith to hold the piece of work, a second arm secured to said sleeve and extending in a direction perpendicular to the axis of the said shaft and on the other side of the first-mentioned arm, two stocks adjustably mounted on the end of the second arm, a stationary pointed member adjustably mounted in one of the said stocks and a claw mounted in the second stock and cooperating with said pointed member in order to hold the model, means actuating the said claw whereby the model can be rotated, a set of bevel gears actuated by the said claw, a shaft which is rotated by the said gears and traverses the two arms tangentially to the fixed pivot shaft, a second set of bevel gears imparting the rotation of the said claw maintaining and rotating the model to the claw maintaining and rotating the piece of work.

2. A pivoting frame for reproducing lathes comprising a stationary shaft, a sleeve clamped to the said shaft and forming a hub, an arm integral therewith and extending in a direction perpendicular to the axis of the shaft, a stock adjustably mounted upon said arm, a claw revoluble in said stock, a second clamped sleeve forming a hub at one end of the shaft, an arm integral with said sleeve and extending in such manner as to form a V with the first-mentioned arm, a stock adjustably mounted in said second arm, a pointed member adjustably mounted in said stock and cooperating with the said claw in order to hold the piece of work, a third arm integral with the first-mentioned sleeve and extending on the opposite side of the shaft to the first and second arms, two stocks placed in a V disposition and adjustably mounted at the end of the third arm, a stationary pointed member adjustably mounted in one of the said stocks and a claw mounted in the second stock and cooperating with said pointed member in order to hold the model, means actuating the said last-named claw whereby the model can be rotated, a set of bevel gears actuated by the said claw, a shaft which is rotated by the said gears and traverses the two arms tangentially to the fixed pivot shaft, a second set of bevel gears imparting the rotation

of the said claw maintaining and rotating the model to the claw maintaining and rotating the piece of work.

3. A pivoting frame for reproducing lathes comprising a stationary shaft, a sleeve clamped to the said shaft and forming a central hub, a central arm integral therewith and extending in a direction, perpendicular to the axis of the shaft, a central stock adjustably mounted upon the said arm, two oppositely-directed claws secured together and revolvably mounted in the said stock, two clamped sleeves forming lateral hubs at the ends of the said shaft, two arms respectively integral therewith and extending in such manner as to form a **W** with the said central arm, two stocks respectively mounted in an adjustable manner upon the two arms, a pointed member disposed in each stock and cooperating respectively with one of the claws of the central stock in order to hold two pieces of work at the same time, a third arm integral with the said central sleeve and extending upon the opposite side of the arm to the said arms in **W** position, two stocks placed in a **V** disposition and adjustably mounted at the end of the third arm, a stationary pointed member adjustably mounted in one of the said stocks and a claw mounted in the second stock and cooperating with said pointed member in order to hold the model, means actuating the said claw whereby the model can be rotated, a set of bevel gears actuated by the said claw, a shaft which is rotated by the said gears and traverses the two arms tangentially to the fixed pivot shaft, a second set of bevel gears imparting the rotation of the said claw maintaining and rotating the model to the claw maintaining and rotating the piece of work.

4. A pivoting frame for reproducing lathes comprising a stationary shaft, a sleeve clamped to the said shaft and forming a hub, an arm integral therewith and extending in a direction perpendicular to the axis of the shaft, a properly machined flat surface formed at the end of the said arm, a stock, a properly machined flat surface formed thereon and cooperating with the flat surface of the arm, means for securing said stock to the arm in an adjustable manner, the said flat surfaces being placed in contact, a claw revolvble in the said stock, a second clamped sleeve forming a hub at the end of the shaft, an arm integral with said sleeve and having a properly machined flat surface at the end, a stock so disposed as to form a **V** with the first-mentioned stock, a flat surface formed at the end of said stock and cooperating with the flat surface of the arm, means for securing the stock and the arm in an adjustable manner, the flat surfaces being placed in contact, a pointed member adjustably mounted in the stock, a third arm integral with the first-mentioned sleeve and extending on the opposite side, a properly machined surface formed at the end of the said arm, two stocks placed in **V** disposition, properly machined surfaces formed at the ends of the said stocks and cooperating with the flat surface of the arm, means for securing said stocks to the arm in an adjustable manner, the flat surfaces being placed in contact, a stationary pointed member adjustably mounted in one of the said stocks and a claw mounted in the second stock and cooperating with said pointed member in order to hold the model, means actuating the said claw whereby the model can be rotated, a set of bevel gears actuated by the said claw, a shaft which is rotated by the said gears and traverses the two arms tangentially to the fixed pivot shaft, a second set of bevel gears imparting the rotation of the said claw maintaining and rotating the model to the claw maintaining and rotating the piece of work.

5. A pivoting frame for reproducing lathes comprising a central shaft, a sleeve clamped to the said shaft and forming a central hub, a central arm integral therewith and extending in a direction perpendicular to the axis of the shaft, two clamped sleeves forming lateral hubs at the ends of the shaft, two lateral arms respectively integral with said lateral sleeves forming a **W** with the said central arm, a **V**-shaped arm integral with the central hub and extending in the opposite direction, properly machined flat surfaces formed at the ends of said arm, five stocks whereof three are situated on one side of the shaft and two on the other side of the same, properly machined flat surfaces formed at the ends of said stocks, means for securing said stocks to the respective arms in an adjustable manner, the flat surfaces being placed in contact, means for holding the model between the two stocks of the said arms placed in the **V** disposition, means for holding the pieces of work at the same time between the stocks of the said arms placed in the **W** disposition, and means for imparting the rotation of the model to the pieces of work.

6. A pivoting frame for reproducing lathes comprising a stationary shaft, a sleeve clamped to the said shaft and forming a hub, an arm integral therewith and extending in a direction perpendicular to the axis of the shaft, a stock adjustably mounted upon the said arm, a claw revolvble in said stock, a second stock situated opposite the first-mentioned stock and cooperating therewith to hold the piece of work, a second arm secured to said sleeve and extending in a direction perpendicular to the axis of the said shaft and on the other side of the first-mentioned arm, two stocks adjustably mounted on the end of the second arm, a stationary pointed

member adjustably mounted in one of the said stocks and a claw mounted in the second stock and cooperating with the said pointed member in order to hold the model, means 5 for actuating the said claw whereby the model can be rotated, a set of bevel gears actuated by the said claw, a shaft which is rotated by the said gears and traverses the two arms tangentially to the fixed pivot shaft, a 10 second set of bevel gears imparting the rota-

tion of the said claw maintaining and rotating the model to the claw maintaining and rotating the piece of work, a tracing device of a known type, and a reaction spring maintaining the said model in contact with said tracing device. 15

In testimony whereof I have signed this specification.

EMILE MARIE PAUL AMANN.
